APPARATUS FOR DECORATING GLASSWARE

John J. Suchocki, Toledo, Ohio, assignor to Owens-Illinois Glass Company, a corporation of Ohio

Application September 29, 1953, Serial No. 383,060

8 Claims. (Cl. 118—219)

The present invention relates to improvements in apparatus for decorating glassware and more particularly pertains to means for applying a gold band to the beaded edge, or rim portion of tumblers and like articles having a surface of revolution.

Considerable difficulty has been experienced in the past in efforts to commercially apply such bands so that they are of uniform width and thickness and do not reveal the point of juncture or overlap of the ends of the applied band.

An object of my invention is to overcome all such objections and provide novel and simple means for rapidly and perfectly banding or coating the rim, both internally and externally of the article of glassware.

A further object is the provision of apparatus which may be adjusted quite easily to accommodate tumblers and the like of various rim diameters.

Other objects will be in part apparent and in part pointed out hereinafter.

In the accompanying drawings:

Fig. 1 is a side elevational view of the invention;

Fig. 2 is a fragmentary plan view with part of the article chuck removed;

Fig. 3 is a front elevational view, partly in section;

Fig. 4 is a sectional elevational view taken along the line 4—4 of Fig. 3;

Fig. 5 is an elevational view of a modified arrangement of the feed rolls; and

Fig. 6 is a detail elevational view of the coating rolls and transfer roller arrangement.

In the illustrated embodiment of my invention I have shown same as including a base member 10 and a frame 11 mounted on said base member. This frame includes an upright arm 12 which carries both the tumbler supporting chuck 13 and other devices, as will be explained hereinafter.

The chuck comprises an inclined post or rod 14, removably anchored at its lower end in a boss 15 on an elongated base plate 15a, the latter extending in a generally upward direction normal to the axis of the post and being longitudinally adjustable on an inclined support 16. This inclined support and base plate have a bolt and slot connection 17 permitting easy adjustment of the post in a radial direction and locking of same in any desired position as determined by the diameter or taper, of the walls of the article being banded. An angular connector bar 18 secures the inclined support 16 to the aforementioned upright arm 12.

The post or rod 14 carries a pair of longitudinally spaced disks 19 which are of suitable diameter and configuration to engage the interior surface of the article at axially spaced points to properly support such article. These disks are slidable axially on the rod. Coil springs 20 urge these disks upwardly a limited distance as determined by cross pins 21 or the like carried by the post or rod 14. Thus the disks normally are in their uppermost or outermost position which has been so established as to prevent any contact between the coating

5

devices and rim of the tumbler incident to mere initial placement of the latter on the chuck. Axial downward movement of the chuck disks is necessary to effect such contact, as will be apparent hereinafter.

The coating means comprises a pair of frusto-conical rotatable coating rolls 22 which are freely rotatable about their axes and mounted upon a pair of arms 23, the latter being pivoted at their outer ends on inclined pivot pins 24 which are carried by brackets 25 attached to the front surface of the upright arm 12. Thus these arms 23 and the rolls 22 may be swung toward and away from each other. The axes of these two rolls are oppositely inclined and spaced apart horizontally, being so relatively positioned that vertical planes extending longitudinally through these axes are substantially parallel and equally spaced at either side of and parallel with a vertical plane through the lengthwise of the axis of the chuck 13.

These rolls also are so relatively positioned that the smaller end of one such roll is closely adjacent to the larger end of the other roll. Also each roll preferably is formed of rubber or like material, or in any event has a resilient rubber facing about its periphery.

By reason of the foregoing it is apparent that a liquid coating material when carried as a film upon the peripheral surfaces of these rolls, may be transferred to the rim R and contiguous circumferential surfaces of a tumbler T or like article incident to the application of downward axial pressure upon the tumbler sufficient to firmly interengage the rim and rolls. Owing to the angular relationship between the tumbler T and the peripheral surfaces of the rolls (Fig. 1) it is apparent that one such roll coats a circumferential portion of the rim or bead R and a narrow contiguous external surface, while the other roll coats the remainder of the rim, or bead and a narrow contiguous internal surface, as well as a fraction of the surface which has already contacted the first roll. Thus the coating is uniformly applied and produces a perfect decorative band. It will be appreciated that the resilient facing of the rolls permits the rim of the tumbler to be pressed thereinto to some extent. Thus the described coating is attained.

It is important that the vertical plane in which the chuck axis lies and along which the chuck is adjusted to accommodate articles of different diameter, be parallel to and medially located between the axes of the rolls. Such insures maximum contact between the rolls and surfaces to be coated. Any departure from such relative positioning of the chuck and rolls progressively lessens the coating effectiveness.

Delivery of the liquid coating material to the rolls 22 (Figs. 1, 3, and 4) is obtained by means including a mechanically driven hard-surfaced transfer roller 26 mounted upon a horizontal shaft 27, the axis of which is positioned medially of the vertical planes in which the roll axes lie. The shaft 27 is journaled in a bearing in the upright arm 12 and by means of a flexible coupling 28 is connected to a speed control device 29, which in turn has operative connection through a shaft 30 with a motor M. Thus the roller 26 is rotated at any desired speed and in turn rotates and delivers coating material to the rolls 22.

It is important that the coating material be distributed as a thin film upon the transfer roller 26. To this end I employ a distributor roller 31 including a soft rubber facing ring 32 for contact with the transfer roller 26. This distributor roller 31 is adapted to be reciprocated incident to its rotation, such being accomplished by incorporating in the mounting a stationary stub shaft 33 threaded with a continuous right and left-hand thread, engaged by a follower carried by the roller 31. This shaft 33 has an eccentric mounting 34 in the upright arm 12 and a screw driver accommodating kerf

2

35 in its outer end. Thus the pressure of this distributor roller upon the transfer roller may be adjusted as required.

Feed rollers 36 are mounted below the distributor roller 31 (Figs. 3 and 4) such being arranged in series with latter and in peripheral rolling contact therewith. These feed rollers are eccentrically mounted in conventional manner to permit relative adjustment of their axes radially. The liquid coating material is fed to one of the feed rolls 36 through a tube 37 from a pressure reservoir 38 mounted upon the aforementioned upright arm 12 by means of a bracket 39 and connected to an air pressure line 40.

Briefly reviewed, the operation involves depositing the liquid coating material upon the feed rollers and transferring same by means of the several rollers including the distributor roller 31 to provide a uniform film upon the transfer roller 26 which in turn applies a thin film to the coating rolls 22. The latter rolls 22 are positively driven by the transfer roller 26. A tumbler T is placed upon the chuck, rim downward. At this point there is no contact between the tumbler and coating rolls 22. Axial downward pressure on the tumbler compresses the springs 20 of the chuck and effects firm contact between the rim R of the article and the coating rolls 22. Immediately these rolls initiate rotation of the tumbler and chuck to progressively coat the rim R and contiguous inside and outside circumferential surfaces of the article. Several revolutions of the article complete the coating operation, the number being determined by the depth of coating desired.

In Fig. 5 I have illustrated a modified form of feed roller arrangement in which the rollers 36 are in a horizontal series instead of staggered as in Fig. 3. Such may well be a space-saving expedient.

Further modifications may be resorted to within the spirit and scope of the appended claims.

I claim:

1. Apparatus of the character described comprising an article supporting chuck having an inclined longitudinal axis about which it is rotatable, resilient means urging the chuck upwardly a limited extent along its axis, a pair of resilient rubber-faced frusto-conical rolls in proximity to the lower end of the chuck, said rolls being mounted for rotation on oppositely inclined substantially co-extensive axes which are spaced apart horizontally and lie in substantially parallel vertical planes, the rolls being so relatively positioned that the smaller diameter end of one roll is adjacent to the larger diameter end of the other roll and the smaller diameter ends of both rolls are lowermost, and means for delivering a liquid coating material and distributing the same over the peripheral surfaces of the rolls.

2. Apparatus of the character described comprising an article supporting chuck having an inclined longitudinal axis about which it is rotatable, resilient means urging the chuck upwardly a limited extent along its axis, a pair of resilient rubber-faced frusto-conical rolls in proximity to the lower end of the chuck, said rolls being mounted for rotation on oppositely inclined substantially co-extensive axes which are spaced apart horizontally and lie in substantially parallel vertical planes, the rolls being so relatively positioned that the smaller diameter end of one roll is adjacent to the larger diameter end of the other roll and the smaller diameter ends of both rolls are lowermost, the axis of the chuck lying in a vertical plane between and substantially parallel with the planes of said inclined axes of the rolls, and means for delivering a liquid coating material and distributing the same over the peripheral surfaces of the rolls.

3. Apparatus of the character described comprising an article supporting chuck having an inclined longitudinal axis about which it is rotatable, resilient means

urging the chuck upwardly a limited extent along its axis, a pair of resilient rubber-faced frusto-conical rolls in proximity to the lower end of the chuck, said rolls being mounted for rotation on oppositely inclined substantially co-extensive axes which are spaced apart horizontally and lie in substantially parallel vertical planes, the rolls being so relatively positioned that the smaller diameter end of one roll is adjacent to the larger diameter end of the other roll and the smaller diameter ends of both rolls are lowermost, a driven horizontal transfer

10 roller for applying liquid coating material to said rolls and having peripheral rolling contact with the latter, the axis of said transfer roller being disposed in a plane which when extended vertically, forms an acute angle with the aforementioned plane of the chuck axis, and means for delivering a liquid coating material and distributing the same over the peripheral surfaces of the rolls.

4. Apparatus of the character described comprising

20 an article supporting chuck having an inclined longitudinal axis about which it is rotatable, resilient means urging the chuck upwardly a limited extent along its axis, a pair of resilient rubber-faced frusto-conical rolls in proximity to the lower end of the chuck, said rolls being mounted for rotation on oppositely inclined substantially co-extensive axes which are spaced apart horizontally and lie in substantially parallel vertical planes, the rolls being so relatively positioned that the smaller diameter end of one roll is adjacent to the larger diameter end of the other roll and the smaller diameter ends of both rolls are lowermost, a driven horizontal transfer

25 roller for applying liquid coating material to said rolls and having peripheral rolling contact with the latter, the axis of said transfer roller being disposed in a plane which when extended vertically, forms an acute angle with the aforementioned plane of the chuck axis, and means for delivering a liquid coating material and distributing the same over the peripheral surfaces of the rolls, the axis of the chuck lying in a vertical plane

30 between and substantially parallel with the planes of said inclined axes of the rolls.

5. Apparatus of the character described comprising an article supporting chuck having an inclined longitudinal axis about which it is rotatable, resilient means urging

45 the chuck upwardly a limited extent along its axis, a pair of resilient rubber-faced frusto-conical rolls in proximity to the lower end of the chuck, said rolls being mounted for rotation on oppositely inclined substantially co-extensive axes which are spaced apart horizontally and lie in substantially parallel vertical planes, the rolls being so relatively positioned that the smaller diameter end of one roll is adjacent to the larger diameter end of the other roll and the smaller diameter ends of both rolls are lowermost, a driven horizontal transfer

50 roller for applying liquid coating material to said rolls and having peripheral rolling contact with the latter, the axis of said transfer roller being disposed in a plane which when extended vertically, forms an acute angle with the aforementioned plane of the chuck axis,

55 a distributor roller in peripheral rolling contact with the transfer roller to effect rotation of the former, means for axially reciprocating the distributor roller to thereby effect distribution of liquid coating material over the peripheral surface of the transfer roller, means for

60 supplying liquid coating material to the peripheral surface of the distributor roller.

6. Apparatus for applying a liquid coating material to the rim surface portion and contiguous band-like exterior and interior surfaces of a tumbler or like article,

70 comprising a pair of frusto-conical rolls each having a resilient peripheral surface, said rolls being arranged side by side and having their axes substantially co-extensive and oppositely inclined to position the peripheral surface of one roll for contact with a circumferential portion of the defined surfaces of the tumbler and the pe-

ripheral surface of the other roll for contact with the other circumferential portion of said surfaces and a fraction of the first named circumferential portion of the defined surfaces, a driven roller for positively rotating said rolls and delivering a liquid coating material to the peripheral surfaces of the latter and a rotatable chuck for supporting a tumbler with its axis inclined and its rim portion and adjacent circumferential side surfaces in rolling contact with the peripheral surfaces of both said rolls.

7. Apparatus for applying a liquid coating material to the rim surface portion and contiguous band-like exterior and interior surfaces of a tumbler or like article, comprising a pair of frusto-conical rolls each having a resilient peripheral surface, said rolls being arranged side by side and having their axes substantially co-extensive and oppositely inclined to position the peripheral surface of one roll for contact with a circumferential portion of the defined surfaces of the tumbler and the peripheral surface of the other roll for contact with the other circumferential portion of said surfaces and a fraction of the first named circumferential portion of the defined surfaces, a driven roller for positively rotating said rolls and delivering a liquid coating material to the peripheral surfaces of the latter and a rotatable 25 chuck for supporting a tumbler with its axis inclined and its rim portion and adjacent circumferential side surfaces in rolling contact with the peripheral surfaces of both said rolls, and resilient means urging the chuck axially away from said rolls.

25
30

8. Apparatus for applying a liquid coating material to the rim surface portion and contiguous band-like exterior and interior surfaces of a tumbler or like article, comprising a pair of frusto-conical rolls each having a 5 resilient peripheral surface, said rolls being arranged side by side and having their axes substantially co-extensive and oppositely inclined to position the peripheral surface of one roll for contact with a circumferential portion of the defined surfaces of the tumbler and the peripheral surface of the other roll for contact with the other circumferential portion of said surfaces and a fraction of the first named circumferential portion of the defined surfaces, a driven roller for positively rotating said rolls and delivering a liquid coating material 10 to the peripheral surfaces of the latter and a rotatable chuck for supporting a tumbler with its axis inclined and its rim portion and adjacent circumferential side surfaces in rolling contact with the peripheral surfaces of both said rolls, and means for bodily adjusting the 15 chuck in a direction normal to its axis to vary the spaced relationship between said axis and the rolls.
